US00D999992S

(12) **United States Design Patent** (10) **Patent No.:** **US D999,992 S**
(45) **Date of Patent:** **** Sep. 26, 2023**

(54) **ELECTRIC DRY SHAVER HEAD**

(71) Applicant: **Braun GmbH**, Kronberg (DE)

(72) Inventors: **Bernhard Sikora**, Kelkheim (DE);
Wolfgang Stegmann, Frankfurt (DE)

(73) Assignee: **Braun GMBH**, Kronberg (DE)

(**) Term: **15 Years**

(21) Appl. No.: **29/782,855**

(22) Filed: **May 10, 2021**

(57) **CLAIM**

The ornamental design for an electric dry shaver head, as shown and described.

DESCRIPTION

FIG. 1 is a perspective view of an electric dry shaver head;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The broken lines illustrate portions of the electric dry shaver head that form no part of the claimed design.

1 Claim, 7 Drawing Sheets
